Patented Apr. 6, 1920.

UNITED STATES PATENT OFFICE.

ARTHUR A. DORSEY, OF LAWRENCE, KANSAS.

VULCANIZER.

1,335,783.

Specification of Letters Patent.

Patented Apr. 6, 1920.

Application filed May 12, 1919. Serial No. 296,479.

To all whom it may concern:

Be it known that I, ARTHUR A. DORSEY, a citizen of the United States, residing at Lawrence, in the county of Douglas and 5 State of Kansas, have invented certain new and useful Improvements in Vulcanizers; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 This invention relates to vulcanizers. The primary object of the invention is to provide a vulcanizer adapted for treating the casings or shoes of pneumatic tires capable of use in connection with motor vehicles.

20 Another object of the invention is to provide a vulcanizer which will be simple in construction, durable, and efficient in operation.

Another object of the invention is to provide a machine so constructed that a uniform heat may be maintained throughout the periphery of the tire, means being also provided whereby the heat to the upper half of a tire may be shut off and I have also provided means for utilizing interchangeable bead molds so that various size tires may be treated in the same apparatus.

Other objects and advantages of the invention will be referred to hereinafter, it 35 being understood that changes in form, proportion and minor details of construction may be resorted to without departing from the spirit of the invention or sacrificing any of its advantages.

40 In the drawings,

Figure I is a perspective view of a machine constructed in accordance with my invention.

Fig. II is a perspective view of a pair of 45 bead molds.

Fig. III is a perspective view of a sectional tread mold.

Fig. IV is a vertical longitudinal sectional view through the device.

50 Fig. V is an enlarged sectional view of the jointure of the two halves, and

Fig. VI is a sectional view of a slightly modified form of the device.

Referring now to the drawings by numerals of reference:

1 designates a stand or base in which a suitable burner chamber 2 is provided, the base being shown as supported upon standards 3 and 4. The burner is adapted to supply heat to a heat chamber of a casing supported upon the base 1. The chamber is formed by a casing consisting of an upper half 5 and a lower half 6 which supports it, the two being secured by fastening devices 7 and 8 passing through the sets of flanges 9 and 10 on the respective halves. When the two halves are brought together, as shown in Fig. I, a circular mold-receiving seat 11 is provided surrounded by a circumferential fluid-directing heat chamber 12 communicating with a water chamber 13 in the base 14 of the member 6. Steam is generated in the base 14 and is adapted to pass from the section 6 to the section 5 through the ports or tubes 15, the ends of the sections being otherwise closed and in the ports 15 are valves 16 whereby said ports may be closed when the top member is removed. The ports 15 extend beyond the ends of the member 6 in the form of dowels, 80 as best seen in Fig. V, so that when the two sections are brought together and the valves 16 moved to opening position, the steam may fill the entire circumferential chamber 12. The seat 11 is in the form of a central circumferential groove adapted to receive a tread mold 17 and the bead molds 18 and 19, the former preferably consisting of two halves and the latter consisting of circumferential rings having inwardly projecting flanges 20 and 21, the alining edges 22 and 23 of which abut, as best seen in Fig. IV, and these mold members are secured in place by the adjusting screws 24 in the bars 25 carried by the screw members 26 and 27 and 85 supported by the casing members 5 and 6.

28 is a pet cock, by means of which pressure may be relieved and 29 is a pressure gage, as will be well understood.

When it is desired to vulcanize or tread a 100 tire, water, which has previously been admitted to the tank 13, is heated by the burner to generate steam at vulcanizing temperature and pressure; the tread molds and bead tanks are then applied to the tire and 105 the assembled parts are placed in the lower section 6, the upper section is then put in place and the two halves are fastened together by the bolts 7 and 8. The bars 25 are then properly positioned and the screws 24 110

are then adjusted to clamp all of the parts together. The valves 16 may then be opened to admit steam to the upper half 5 and the tire may remain in the machine a sufficient 5 length of time to complete the desired operation.

When it is desired to remove the tire, the valves 16 will first be shut off, the upper half of the casing 5 removed, the clamps released 10 and the tire, together with the molds, may be taken out without releasing the steam pressure because this cannot escape from the casing 6 on account of the valves 16. When the steam pressure is too high, however, this 15 may be relieved by opening the pet cock 28 and observing the pressure gage 29. It is to be understood, of course, that different size molds may be employed for different size tires; therefore, the device is capable of 20 use in connection with tires of the same diameters but different sizes of tread.

It will be observed that when the tire is in place, the heat from the steam will be communicated direct to the rubber through the 25 wall 30 and the molds 17, 18 and 19, and since the steam will be directed at a uniform pressure about the entire periphery of the tire casing or shoe, a uniform heat will be applied.

30 In Fig. VI I have shown a slightly modified form of the device in which communication may be had between the upper and lower halves through the medium of a flexible connection or hose 15'. This will enable the 35 upper half to be removed from the lower half without breaking the connection so that steam pressure may be maintained in both halves. By reference to Fig. III it will be observed that the halves of the tread molds

may be connected together by latches 31 engaging sockets 32, it being understood that the tread molds may be constructed of various sizes to accommodate different tires.

By reference to Fig. I it will be apparent that a pet cock 33 may be installed in the 45 upper half of the mold.

What I claim and desire to secure by Letters-Patent is:

1. A vulcanizer comprising a circular casing consisting of an upper semi-circular 50 member and a lower semi-circular member, the ends of the members having communication through hollow dowels carried by one section and passing into the other, valves for cutting off communication between the sections, and means for connecting the two members.

2. A vulcanizer comprising a circular casing consisting of an upper semi-circular member and a lower semi-circular member, 60 the ends of the members having communication through hollow dowels carried by one section and passing into the other, valves in the hollow dowels for cutting off communication between the sections, and means for 65 connecting the two members.

3. A vulcanizer comprising a circular casing consisting of an upper semi-circular member and a lower semi-circular member, 70 the ends of the members having communication through hollow dowels carried by one section and passing into the other, valves for cutting off communication between the sections, removable circumferential tread and 75 bead molds receivable within the casing, and means for connecting the two members.

In testimony whereof I affix my signature.

ARTHUR A. DORSEY.
